JOHN SIDDONS, OF ROCHESTER, NEW YORK

Letters Patent No. 95,390, dated September 28, 1869.

IMPROVED METALLIC ROOF.

The Schedule referred to in these Letters Patent and making part of the same.

To all whom it may concern:

Be it known that I, JOHN SIDDONS, of Rochester, in the county of Monroe, and State of New York, have invented certain new and useful Improvements in the Construction of Metallic Roofs; and I do hereby declare that the following is a full, clear, and exact description thereof, reference being had to the accompanying drawings, making part of this specification, in which:

Figure 1 is a section of a portion of a roof made upon my plan, taken transversely through the ribs B B.

Figure 2 is a longitudinal section, showing a rib in elevation.

Figure 3 is an enlarged section of a rib, B, showing the formation of the joint between the sheets a a'.

The object of my invention, the nature of which will be understood by reference to the drawings and specifications, is to provide a metallic roof that will not warp and open at the seams by expansion and contraction, and will be impervious to water, particularly when bodies of snow lie and melt upon it.

To enable others to make and use my invention, I will describe its construction.

I make my improved roof of any metal in common use for such purpose, providing the wooden ribs B B, fig. 1, running at right angles to the ridge-pole, upon which ribs the ends of the sheets a a' are joined.

These ribs stiffen the roof and lift the seams of the sheets above any ordinary depth of water that may fall upon it.

They are made triangular in section, or in other suitable shape, and the sheets a a' are bent near the end, in such a manner that they shall lie against the sides of the ribs, and project a suitable distance above them, as shown at b', fig. 1, one sheet being somewhat longer than that on the opposite side of the rib, as shown by the dotted line.

Between the sheets where they rise above the ribs, I introduce strips of packing, r, made of cloth, felt, or other suitable material, saturated with paint or oil.

This packing is doubled over the edge of the short sheets, as seen at b', fig. 1, and is retained in its place while the seam is being made, by cleats c, figs. 1 and 2, shown in dotted lines in fig. 2, placed at suitable points along the ribs, which cleats are bent over at their upper ends to clasp the packing tightly against the short sheets, and are brought down and nailed, at their lower ends, to the roof.

The cleats c also retain the sheets a in their places, and prevent their ends from lifting by expansion or other causes.

The longer sheets are next applied, and bent over both packing and cleats at the edges of the short sheets, as shown at b', fig. 1, after which both sheets, together with the packing, are given another turn, forming a double fold or seam, b, with the packing interposed, as indicated by the red lines in figs. 1 and 3.

This seam also secures the sheets a and a' firmly together, and consequently all are held down by the cleats c.

The transverse joints are made by overlapping the sheets upon each other to a suitable distance, and inserting between them, at the edges, a strip of packing similar to that used in the longitudinal seams, as shown at x x', fig. 2, after which nails are driven through the whole, and clinched on the under side of the roof-board A.

This arrangement makes a perfectly tight joint, and also prevents the sheets from warping or lifting, as the nails have sufficient elasticity in the wood to allow expansion and contraction.

The ribs B B are brought down to the gutter-plate d, fig. 2, upon which I provide the caps e, either soldered to the gutter, or swaged up from the same, at proper distances, to correspond with the location of the ribs B.

The ribs are chamfered suitably at their lower ends, so as to enter the recesses formed by the caps e, and the packing x' is continued over these caps, so that the sheets a' which are somewhat extended at the point i, may be bent down tightly upon it before the fold b is made.

This mode of securing the connection of the ribs with the gutter-plate, effectually prevents the water from setting back under the sheets.

The seam or lock b may be given another fold, and laid down upon the side of the rib, if it is desired to reduce the height of the projections upon the roof.

I am not necessarily confined to the triangular shape of the ribs B, but I prefer that form, as the easiest to construct, and as fully as efficient as any other.

The sheets a a' are bent to their proper shape in a press before being laid, and the caps e, in the gutter-plate, can be formed in a similar manner.

What I claim as my invention, and desire to secure by Letters Patent, is—

In combination with the ribs B, sheets a and a', and double-locked seam b, the fibrous packing r, as shown and described, and for the purposes set forth.

JNO. SIDDONS.
